UNITED STATES PATENT OFFICE.

CHARLES W. RENNER, OF ALTOONA, PENNSYLVANIA.

CAR-ROOF CONSTRUCTION.

1,079,800.

Specification of Letters Patent. Patented Nov. 25, 1913.

Application filed November 1, 1912. Serial No. 729,170.

To all whom it may concern:

Be it known that I, CHARLES W. RENNER, a citizen of the United States, residing at Altoona, in the county of Blair and State of Pennsylvania, have invented certain new and useful Improvements in Car-Roof Construction, of which the following is a specification.

This invention relates to the subject of car roofs, and particularly to a type of roof that may be advantageously used in the construction of freight cars, although not at all necessarily limited to this class of railway rolling stock.

Many of the roofs now in use, employ wooden construction, together with iron or steel frame work. In this method the wooden parts are apt to quickly rot away and, of course, render the roof of short service. Therefore, the present methods involve considerable expense for their maintenance and repair.

Accordingly, the general object of the present invention is to provide a simple, practical, and durable roof construction that is particularly adapted for use on cars of the all-steel type that are now coming into general use. The structure set forth in this case is made entirely of iron or steel, and is so made that any and all parts thereof may be quickly replaced and easily repaired. The durability of metal, of course, being greater than that of wood, makes the cost of maintenance in general much lower than otherwise would be the case where wood, or wood parts are employed.

Another object of this invention is to provide a construction wherein the roof sheets, that are used in connection therewith, extend from one side of the car to the other. This does away with the necessity of having a joint at the center of the car, which is continually needing attention where it exists in actual use. It will also be observed with reference to the roof sheets extending from one side of the car to the other, that the same, when properly locked in the roof frames greatly strengthens the entire car body and increases the stability thereof.

A further object of the invention is to provide channeled metal carlines, that are provided with means for connecting each other through the medium of a metal purlin, and are adapted to receive the inturned edges of the roof sheets in their channeled portions. In order to lock the sheets within the carline

there is employed a removable locking bar that is adapted to slide in the channels of the carlines, and when secured therein the said bar holds the roof sheets in the carline. 60

A still further object of the present invention is to provide a metal roof frame construction that will permit the use of bridge blocks for supporting the running board, in such a manner that the interior of the car is 65 at all times protected against a leak occurring at this particular point.

With these and many other objects in view, which will more readily appear to those skilled in the art as the description of the 70 case proceeds, the same consists in the novel construction, combination and arrangement of parts hereinafter more fully described, illustrated and claimed.

A preferred and practical embodiment of 75 the invention is shown in the accompanying drawings, in which—

Figure 1 is a perspective view, partly in section, of a portion of a car having the improved roof construction. Fig. 2 is a vertical sectional view of one of the carlines. Fig. 3 is a cross sectional view of a carline and a bridge block supporting the running board. Fig. 4 is a view similar to Fig. 3 showing a modification. Fig. 5 is a detail 85 cross sectional view of one of the carlines showing a modified form of channel and locking bar. Fig. 6 is a perspective view of a channeled metal carline. Figs. 7 and 8 are detailed cross sectional views of a carline 90 showing different forms of channels. Fig. 9 is a perspective view of the locking bar employed in connection with the carline. Figs. 10 and 11 are detailed views of a locking bar, Fig. 10 showing a cross section, and 95 Fig. 11 the end thereof, that terminates at the center of the car. Fig. 12 is a perspective view of a bridge-block. Figs. 13 and 14 are detail sectional views of bridge blocks. Fig. 15 is a longitudinal sectional view of a 100 pressed steel carline. Fig. 16 is a detail cross sectional view on the line $x-y$ of Fig. 15. Fig. 17 is a perspective view of a pressed steel carline.

Similar reference numerals designate corresponding parts throughout the several figures of the drawings.

Referring specifically to the drawing, the letter C designates a car body, which may be either of wood or steel, and the letter F 110 designates the frame work around the top of the car body.

The reference numeral 1 refers to a channeled metal carline, which may be made of iron or pressed steel whichever is preferred. The channeled portion of the carline, which is designated as 2, extends the full length of the carline, and the sides of said channeled portion preferably converge upwardly. It will of course be understood that the carline 1 extends from one side of the car body to the other, that is, it spans the car body from one side to the other, and engages the said frame with the saddle portions 3. These saddle portions are provided with holes 4 to permit the ends of the carline to be securely bolted to the car frame. The said carline 1 is also provided along each side thereof with a plurality of perforated fastening ears 5. The said fastening ears 5, are designed to support the metal purlins 6, the latter also being secured to the said ears 5. This construction unites one carline with another, and also provides a support for the roof sheets 7 which are designed to span the portion between each carline. The said roof sheets 7 are undivided, that is they extend from one side of the car body to the other, and the edges thereof are turned downwardly as indicated at 8. The said inturned edges 8 of the roof sheets 7 are adapted to enter the channeled portions 2 of the carline, thereby causing the roof sheet to conform with the line of curvature of the carline, and also to a degree serve to hold the roof sheets in place. In order to positively and securely hold the roof sheets in place, and lock the same within the channeled portions of the carline, there is provided a locking bar 9, which is of substantially T-shape in cross section. This locking bar is provided with a locking tongue 10 which is of the same shape as the channel in the carline. It will also be observed that the said locking bars 9 terminate near the central portion of the carline, and have at their inner or terminal ends a socket member 11. The construction of the said locking bar permits the same to be slid in the channel portion of the carline after the edges of the roof sheets are placed within the channel portion 2, thus locking the roof sheet in the carline. The outer end of the locking bar is provided with a hole 12 which is adapted to receive a suitable fastening which will also enter the hole 4^a on the outer end of the carline. This fastening will, of course, prevent the locking bar from sliding out of the channel of the carline. From Fig. 5 it will be observed that the channeled portion 2^a of the carline 1 has vertical sides, and that the edges 8 of the roof sheet 7 are locked therein by the locking bar 9^a which has a tongue 10^a whose sides are also vertical. This construction will permit of the locking bar being pushed down into the carline and thereby lock the

roof sheets in place, instead of sliding the locking bar into place as is shown in the other instances. As has been pointed out before, it will be evident that two locking bars are required to lock the roof sheets in each carline, and that the said locking bars meet at the center of the roof. At this point there is placed a bridge block 13 which is provided with the down turned flanges 14 that are adapted to engage over the sides of the locking bars at their meeting portion. The underside of the bridge blocks 13 is provided with downwardly projecting studs 15 which are adapted to enter the sockets 16 in the top of the locking bar. These studs 15 when in the sockets 16 serve to hold the locking bars 9 together at their inner parts, in addition to the fastenings at their outer ends which enter the car frame. The bridge block 13 is further provided with a central fastening receiving hole 17, and bolt holes 18^a in the top portion thereof to receive fastening bolts from the running board 18. A bolt 19 is employed for holding the bridge block 13 to the carline 9, the said bolt also serving to firmly hold, by pressure upon the bridge block, all of the parts at the center of the carline, firmly in place.

The modified form of carline shown in Fig. 8, and also in Fig. 4, employs for locking the bridge block 13 to the carline, a T head bolt 19^a, the T portion of said bolt engaging the shouldered portion 20 of the carline 1^a, and thereby firmly holding the parts at the center of the carline firmly together as in the other instance. In connection with the fastening members 19 and 19^a it will be observed that they are surrounded by the sockets 11 formed in the meeting ends of the locking bars to come flush together and thereby make a tight joint at their meeting ends.

The construction illustrated in Figs. 1 to 12 inclusive shows the application of the invention when iron frame work is used, while Figs. 13 to 15 inclusive show the invention used with pressed steel. In this connection, it will be observed that the construction of the channeled carline is substantially the same as that of the one shown in Fig. 6, except that its outer portion, instead of being provided with a saddle, is provided with the perforated projecting portion 20, and the perforated angled portion 21 which is adapted to be secured to the car frame. The same type of locking bar 9 is employed with the pressed steel carline, and is fastened at its outer end to the perforated projection 20 by the bolt 20^a. In the pressed steel form of carline at the center thereof is welded an upstanding sleeve 22 which is adapted to receive the fastening bolt 19^b which is adapted to secure the bridge block 13 to the parts at the center of the carline. The welding of this sleeve to the carline 130

makes an absolutely tight and water proof connection between the elements at the center of the roof, and thereby prevents the water from entering the interior of the car.

5 From the foregoing description, it is believed that it will be readily apparent that the locking bars 9 can be easily removed or replaced so as to effect the removal of the roof sheets, and that the bridge blocks can 10 also be removed for repairing or replacing parts, with very little trouble.

In connection with the carline 9, it will be observed from Fig. 1 that the carline that happens to come at the end of the car is 15 provided with a flange 9^b which overhangs the sides of the carline that is exposed by reason of the fact that there is no roof sheet extending therefrom. This flange prevents water from beating up under the locking 20 bar, and also gives the ends of the car a finished appearance.

I claim:

1. A car roof construction, comprising in combination with the car body, a plurality 25 of channeled metal carlines extending transversely thereof, roof sheets spanning said carlines and extending from one side of the car to the other, removable means for holding the roof sheets into the carlines, said 30 means provided with sockets, bridge blocks at the meeting edges of said removable

means, blocks provided with downwardly projecting studs adapted to enter the sockets on said removable means, flanges on said bridge blocks adapted to fit over the edges 35 of said removable means, and means for locking the bridge block to the carline.

2. A car roof construction, comprising in combination with the car body, a plurality 40 of channeled pressed steel carlines extending transversely thereof, roof sheets for spanning the carlines, flanges on said roof sheets for entering the channels of the carlines, removable locking bars, provided with 45 sockets, for securing the roof sheets in the carlines, upstanding sleeves welded at one end to the carlines, bridge blocks at the junction of the locking bars, said blocks being provided with a central bolt-receiving 50 hole adapted to fit over the said upstanding sleeve, studs projecting from the underside of the bridge blocks and adapted to fit into the sockets on the locking bars, means for locking the bridge blocks to the carlines, 55 and flanges depending from the said bridge blocks.

In testimony whereof I hereunto affix my signature in the presence of two witnesses.

CHARLES W. RENNER.
